UNITED STATES PATENT OFFICE.

ALPHONSE VÉZINA, OF HEDLEYVILLE, CANADA.

CAR-COUPING.

SPECIFICATION forming part of Letters Patent No. 681,462, dated August 27, 1901.

Application filed December 10, 1900. Serial No. 39,253. (No model.)

To all whom it may concern:

Be it known that I, ALPHONSE VÉZINA, a subject of Her Majesty the Queen of Great Britain, residing at Hedleyville, county of Quebec, Province of Quebec, Canada, have invented certain new and useful Improvements in Car-Couplers; and I do hereby declare that the following is a full, clear, and exact description of the invention, such as will enable others skilled in the art to which it appertains to make and use the same.

My invention relates to improvements in car-couplers of that class known as "link-and-pin" couplers; and one object of the invention is to provide an improved construction, including the means for holding a gravity-pin normally in a raised position ready for engagement with a link on an approaching draw-head, whereby the car will be automatically coupled.

Further objects of the invention are to provide means operable by a brakeman stationed on the side of the car for the purpose of disconnecting the coupling-pin from the link, and thereby uncouple the cars without requiring the brakeman to pass between them, to provide means by which the pin-holding slide will be automatically returned to its normal position, and finally to slidably mount the draw-head, so as to yield somewhat when struck by an approaching draw-head.

The invention consists in the novel construction and arrangement of parts, which will be hereinafter fully described and claimed.

In the drawings hereto annexed, forming a part of this specification, Figure 1 is an inverted or bottom plan view of a portion of a car equipped with an automatic coupler embodying my invention. Fig. 2 is a front view thereof. Fig. 3 is a longitudinal vertical section in the plane of the dotted line 3 3 on Fig. 1. Fig. 4 is a transverse horizontal section through the draw-bar and its supporting means, the plane of the section being indicated by the dotted line 4 4 on Fig. 3. Fig. 5 is an enlarged detail view of the coupling-pin and certain of the parts associated therewith.

The same numerals of reference denote like parts in each figure of the drawings.

10 designates a portion of the framework of a car, which includes the transverse beams 11 and 12. To the end of the front beam 11 is se-

cured a keeper 13, and in the rear beam 12 is formed a transverse opening 14, the latter being in alignment with the space of the keeper 13. A draw-bar 15 is mounted slidably in the keeper 13 and the slot 14 of said rear beam, and in order to hold this draw-bar in its projected operative position I have provided the spring-pressure bar 16, the latter being arranged in rear of the beam 12 and in position for engagement with the rear extremity of said draw-bar. Said spring-bar 16 extends transversely across the car for its end portions to engage with the staple or eyebolts 17, which are fastened to the car-frame; but it is evident that this spring-bar may be otherwise attached to the car-frame and that another type of spring may be substituted for the straight bar herein shown as one embodiment of the invention.

The draw-bar is provided at points intermediate of its length with the flanges 18, arranged to project from opposite sides of said bar, and the rear portion of the draw-bar is reduced in size, as at 19, so as to fit slidably in the opening 14 of the rear transverse beam 12. The draw-bar is disposed within a housing which limits positively the endwise movement of said bar under the repression of the spring and the shock of meeting draw-heads. This housing consists of the side plates 20 21 and the bottom plate 22. The side plates extend between the keeper 13 and the beam 12, and said plates are provided in their inner faces with the grooves or recesses 24, in which are received the flanges of the draw-bar. The bottom plate 22 is fastened in any approved way to the lower edges of the side plate—as, for example, by screws—and this bottom plate rests snugly against the under side of the draw-bar. The side plates of the housing are held against movement by engaging with the keeper of the rear cross-beam, and the recesses or grooves in these side plates are somewhat longer than the flanges of the draw-bar in order to permit the latter to have the desired endwise movement, whereby the shoulders of the recessed plates 20 21 limit the endwise movement of the draw-bar.

The front end of the draw-bar is fashioned to provide a draw-head 25, in which is produced a link-chamber 26 and a vertical pin-opening 27. In this link-chamber is slidably

fitted a pin-holding slide 28, the latter adapted to traverse the pin-opening and being pressed normally in an outward direction by the agency of a coiled spring 29, the latter contained in a reduced rear portion or extension of the link-chamber. The coupling-pin 30 is fitted loosely in the pin-opening 27 of the draw-head, and to the upper extremity of this pin is attached a guide-plate 31, the coupling-pin being headed, as at 34, to retain the plate in connection therewith. Said guide-plate is slidably fitted in the longitudinal slot 32 of a vertical guide 33, the latter having a foot arranged to rest upon the draw-head and to be secured firmly thereto in any approved way, whereby the vertical guide lies adjacent to the pin, so as to direct the up and down movements of the guide-plate and the coupling-pin to which said plate is secured. This guide-plate is formed with the lateral lugs 34^a, that are adapted to ride against the rear side of the vertical guide, and the plate is furthermore provided with the rearwardly-extending pintle 35, the latter being disposed on the opposite side of the vertical guide from the gravity-pin. 37 38 designate the uncoupling-levers, the same being arranged on opposite sides of the draw-head and having their inner ends disposed in overlapping relation, so as to be mounted loosely on the pintle 35 of the guide-plate. Each lever is fulcrumed at a point intermediate of its length on a bracket 39, attached to the car, and the lever has a handle portion disposed at or close to the side of the car, and, as shown in Figs. 1, 2, and 3, said levers are capable of a movement endwise of the forwardly-extending portion of the bracket 39. It will therefore be seen that provision is made for a yielding movement of the draw-bar without disarranging the mechanism for operating the pin. As the draw-bar yields the pin, guide, guide-plate, and uncoupling-levers move correspondingly, and hence there is no liability of a disarrangement of the positive connections of these parts, and while said uncoupling-levers have a slideable movement on their pivots they are prevented from passing from off of their pivot-points, owing to the presence of the lugs 34^a, which prevent a forward movement of the front ends of said levers.

A link 40 is intended to be connected to a

draw-head on an approaching car, and when the coupling-pin is lifted and engaged by the holding-slide the coupling is in condition for automatic operation. The link is intended to enter the chamber of the draw-head, so as to engage with the slide therein and force the latter in an upward direction, whereupon the pin is released, and it is caused to fall by gravity into engagement with the link, thus coupling the cars without requiring the brakeman to pass between them for adjustment of the pin. The pin may be raised by a brakeman stationed on one side of the car, who is only required to operate one lever in a direction to lift the pin, thus withdrawing it from the path of the link and allowing the spring-repression slide to move in an outward direction on withdrawal of the link, whereby the slide again sustains the pin in a raised position, ready for automatic coupling of another car.

Changes within the scope of the appended claim may be made in the form and proportion of some of the parts while their essential features are retained and the spirit of the invention is embodied. Hence I do not desire to be limited to the precise form of all the parts as shown, reserving the right to vary therefrom.

I claim—

In a car-coupler, the combination with a yielding draw-head, and a gravity-pin therein, of a vertically-slotted guide mounted on the draw-head adjacent to the pin, a guide-plate attached to the pin and fitted slidably in the slot of the guide, and uncoupling-levers each having a pivotal and slideable movement on its support and loosely and positively connected with said guide-plate, the slideable movement being in a direction corresponding with that of the yielding draw-head, whereby said draw-head may yield under pressure without disarranging the relative positions of the pin and its operating mechanism or destroying the positive connections of said pin and mechanism, substantially as described.

In witness whereof I have hereunto set my hand in the presence of two witnesses.

ALPHONSE VÉZINA.
